UNITED STATES PATENT OFFICE.

MERTON D. PHELAN, OF BOSTON, MASSACHUSETTS, ASSIGNOR, BY MESNE ASSIGNMENTS, TO MANUFACTURERS MACHINE COMPANY, OF MONTCLAIR, NEW JERSEY, A CORPORATION OF NEW JERSEY.

METALLIC-FASTENING MACHINE.

953,003.

Specification of Letters Patent. Patented May 17, 1910.

Application filed January 11, 1907, Serial No. 351,785. Renewed November 22, 1909. Serial No. 529,314.

To all whom it may concern:

Be it known that I, MERTON D. PHELAN, a citizen of the United States, residing at Boston, in the county of Suffolk and State of Massachusetts, have invented an Improvement in Metallic-Fastening Machines, of which the following description, in connection with the accompanying drawings, is a specification, like numerals on the drawings 10 representing like parts.

This invention relates to machines for inserting fasteners and more particularly to a machine for making such fasteners from a continuous wire or strip and for driving them as made.

My invention is particularly useful in connection with what is known as a "slugging" machine employed in the manufacture of boots and shoes.

20 My invention aims especially to improve such machines for the purpose of increasing the speed and consequent output, as well as for improving the quality of work produced.

My invention will be best understood from 25 a disclosure of one embodiment thereof shown in the accompanying drawings and selected for the purpose of illustrating said invention but without any intention of limiting my invention thereto.

30 In the drawings accompanying this description; Figure 1, illustrates in side elevation a machine made in accordance with the selected embodiment of my invention. Fig. 2, is an elevation of the opposite side of 35 said machine but upon an enlarged scale. Fig. 3, is a front elevation of the machine, Fig. 1, also upon an enlarged scale. Fig. 4, is a diagrammatic detail illustrating the driver carrier and the cam for reciprocating 40 the same; Fig. 5, an irregular horizontal section on the dotted line 5-5 Fig. 1. Fig. 6, a partial side elevation of the parts shown in Fig. 5; Fig. 7, a cross sectional detail on the dotted line 7-7 Fig. 5; Figs. 8 and 9 details in end view and side elevation respectively, of one form of cutting block employed 45 in the machine. Fig. 10, a vertical sectional detail illustrating the wire feeding mechanism detached, the same being approximately 50 a section on the irregular dotted line 10-10 Fig. 2. Fig. 11, a plan view of the feeding pawl and its carrier Fig. 10. Fig. 12 a sectional detail on the dotted line 12-12 Fig. 10. Fig. 13, another diagram-

matic or detail view, illustrating the awl 55 driving and work feeding means detached, said view being in effect a front view with the driver and awl carriers broken away to show the parts in the rear, and Fig. 14, a detail of parts shown in Fig. 13 to be referred to.

In the particular embodiment of my invention selected for illustration herein, and shown in the drawings referring first to Fig. 1, the machine is mounted upon any desired 65 column 1, the same carrying the machine head 2, provided with suitable bearings for the horizontal main shaft 3. This shaft at its rear end, outside the head, is provided with a suitable clutch device 4 by which it 70 may at will, be connected with and disconnected from a continuously running pulley 5.

Fast on the main shaft within the limits of the head is a bevel gear 6, that drives a mating gear 7, on the upper end of a vertical shaft 8, journaled in the head, said shaft at its lower end (see Figs. 2 and 5) having fast upon it a cam 9. This cam rotates continuously while the machine is in operation, between suitable gibs 10, on and to reciprocate the horizontally arranged 75 sliding carrier 11, Fig. 5. Said shaft 11 at its forward end, at the left Figs. 5 and 6, carries the vertically arranged cutting block 12, shown as provided at its upper end with 80 a flange upon which it is seated, it being also provided with a vertical axial wire passage 13, into which the wire is fed from which a fastener is to be made. This cutting block is held fixedly in position by a clamping 85 screw 14 (see Fig. 6).

Immediately above the cutting block 13, in the rearmost position of the latter, is arranged a co-operative cutting block 15, (see Fig. 6) the same being mounted in a block 95 16, removably secured in and to form a part of the machine head. The cutting block 15, is shown in detail in Figs. 8 and 9 and is adapted in this instance, to act upon wire having a rectangular cross section. Said 100 block as shown consists of a tubular member flattened at one side to be acted upon laterally by the clamping screw 17, Fig. 6, which holds it in position; it is seated vertically, against an adjusting screw 18, which 105 has a central orifice that registers with the wire passage of the cutting block in order that the wire may be led downward through

said screw to and through said block. The block 15, see Fig. 8, has a slot 19, milled to and slightly past the center of the block and which intercepts a previously drilled hole 5 that receives a pin 20 to close said slot, said pin having a flattened base to constitute one of the side walls of the rectangular wire receiving passage of the block.

When the cutter carrier 11 is in its rear-most position, at the right Figs. 5 and 6, the wire receiving passage 13 of this cutter block 12, registers with the wire receiving passage of the co-operating cutter block 15, above it, and at such time a length of wire is fed downward through the cutter 15, into the cutter 13. As said cutter carrier is moved forward by its cam 9, the cutter block 12, shears or cuts off the wire between it and its co-operating cutter 15, and then serves as a fastener carrier to carry the severed length of wire which is now a fastener or part thereof, forward into position Fig. 6, to permit said fastener to be driven downward through the cutter 12, into the work beneath. Directly beneath the movable cutter block 12, is a suitable work plate 21, the same being carried on suitable arms 22, (see Fig. 5), depending from the machine head or a part thereof. This work plate has an orifice 23, through which the fasteners may be driven into the work.

To permit of needed adjustment of the movable cutter 12, to cause it always to register with its co-operating cutter 15, the said cutter carrier 11 is made in two parts as shown best in Fig. 5. The rear part containing the cam gibs, is formed at its forward or left hand end Fig. 5, as a socket to receive the other or forward part or member 40 of said carrier. The said forward end is screw threaded at 24, to receive a nut 25 which enters a suitable recess 26, provided therefor in the socketed end of the gib carrier member. Said nut is shown provided 45 with pin holes, to receive a pin by which said nut may be turned to cause relative adjustment of the two members, to vary the position of the cutter 12, as required. The threaded member is grooved at its upper side 50 to receive a screw 27, see Fig. 7, which holds the two parts of the carrier against relative rotation and, for the purpose of clamping the parts in adjusted position, the socketed member, see Fig. 7, is split at one side and 55 provided with a clamping screw 28, by which it may be closed upon and to grip the contained threaded member.

Referring now again to Fig. 1, the main shaft 3, at its extreme forward end is provided with a driver cam 29. This cam, see Fig. 4, plays between gibs 30 on the vertically reciprocable driver carrier or bar 31, mounted in suitable ways in the machine head. At its lower end, said driver bar has 65 clamped within it a suitable driver 32 which,

upon reciprocation of its carrying bar, is caused to descend through the nut carrier or cutter 12, positioned beneath it, to drive the fastener therein, out through the lower end thereof, into the work positioned beneath and in contact with the work plate referred to. 70

The wire from which the fasteners are to be formed, may be taken from any suitable source. In the present instance, it is carried as a coil 33, (see Fig. 1) on a reel support 75 mounted on the machine head. From this reel, (see Fig. 10) the wire is led down to the tubular screw 18, previously referred to.

To feed the wire forward at the required times and in the required lengths, I have provided the following mechanism. Fast upon the main shaft 3, Fig. 10, is a cam 34, embraced by a yoked arm of a lever 35, fulcrumed at 36, on an arm of the frame. The depending arm of the lever 35, is grooved 85 at 37, at its inner face, (see dotted lines Fig. 10 and full lines, Fig. 2) to receive a slide block carried by a pin 38, adjustable in the slotted arm of a bell crank 39, fulcrumed at 40, also on an arm of the machine head. The inwardly extended arm of said bell crank is marked 41, Fig. 11, the same having its outer end at one side, slotted radially to receive a block 42 to which is fulcrumed at 43 a U shaped pawl 44. This pawl at its 90 elbow is pivotally connected by a screw 45 to a second arm 46, loosely mounted on the fulcrum 40, and to hold in frictional engagement therewith or with the bell crank that is fast thereon, in suitable manner. Herein 95 the hub of said second arm 46 (see Fig. 11) is arranged between two friction washers 47 maintained in frictional relationship with the arm 46, by a spring 48, seated against a nut 49, threaded upon the reduced end of the fulcrum stud 40. The active or toothed end of said pawl 44, stands opposite the continuous wall of a guide way or plate 50 on the said arm 46, and is held against undue movement relative to said arm 46, by a stop 100 51 on the latter. The arrangement is such that, if the pawl carrying end of the bell crank be elevated, it will first tip the pawl about its pivot 45, on and relative to the arm 46, to cause said pawl to free itself from the wire or until it is arrested by the back stop 105 51 after which both arms will rise together. Opposite movement of the said bell crank, however, causes an opposite turning movement of the pawl 44 to cause its toothed end 110 to move to the right to grip the wire between said end and the guide plate 50, after which, it being impossible for the pawl to turn further, the said two arms will descend together, this time, however, carrying the wire 115 with them. The frictional mounting of the arm 46 relative to the bell carrying arm 41 permits of the relative movement of the pawl to the wire for the purpose of freeing itself from, and engaging, said wire, to feed the 120 130

latter. Since there can be no feeding movement of the pawl until this turning movement has been arrested by contact with the wire, it follows that there can be no slip between the pawl and the wire because, the greater the resistance to the travel of the wire, the greater also will be the grip to cause the wire to be fed.

Between the feed pawl 44, and the tubular 10 guide screw 18 I have arranged a pair of back stop pawls 52, (see Fig. 10,) they being held by a spring 53, always in frictional engagement with opposite sides of the wire, but at such an angle therewith, that they 15 will permit free travel of the wire to the cutters yet will resist and effectively arrest any retrograde movement of the wire. These pawls are mounted in a suitable carrier block 54, secured in the machine head 20 and which is provided with a guide way through which said wire is carried to and between said pawls. The parts are so timed that when the wire is fed forward for the 25 new fastening and the fastener or nail carrier is in its rearmost position to receive it, and the feed pawl returns for a new nip of the wire during the time in which the projected wire is being supplied to the carrier, and carried forward for driving.

30 The machine may be used with or without an awl, and awl feed, but for most classes of work, I prefer to use both the awl and the awl feed. To this end, (see Figs. 1, 3 and 4) I have mounted in the head, close beside 35 the driver bar 31, an awl bar 55. This bar near its upper end, (see Fig. 1,) has a stud 56, to which is jointed the upper end of a link 57, connected at its lower end, (see Figs. 3 and 13), with one arm of a yoke 58, fulcrumed at 59 on the machine head. Said 40 yoke is provided with a pair of rollers or studs 60, 61, which run respectively on cams 62, 63, placed side by side on the main shaft 3. These cams operate to oscillate said yoke 45 effectively in both directions, thereby through the said link 57 to reciprocate said awl bar 55, and give to the awl, to be described, its vertical movement to cause it to enter and leave the work. At its lower end, said awl 50 bar, (see Fig. 13), is provided, with a laterally extended foot 64, in which slides a block 65, having a depending arm 66 in which is clamped the awl 67. This block and its awl are therefore caused to move vertically with 55 the awl bar to enter and leave the work as stated, and are caused to slide in the foot of said bar to furnish lateral feeding movement to the awl, by the follow mechanism. Said block 65, near its outer end, Fig. 13, 60 has a vertical guide way 68, for a block 69 (see Fig. 14) fulcrumed at 70 in a depending arm 71 of a lever fulcrumed at 72 on the machine head. The upwardly extended arm of said lever is on the opposite end of the 65 fulcrum 72 (see Fig. 1) and, said upwardly

extended arm is grooved at its inner or rear face to receive a slide block, shown in dotted lines, Figs. 13, and 14, loosely mounted upon a stud 73, in the slotted arm 74, of a lever fulcrumed at 75 on a stud on the machine 70 head. The upper end of said lever 74 is formed as a yoke, 76, having its arms provided respectively with rolls 77, 78, Fig. 13, that travel respectively on cams 79, and 80, on the main shaft 3. Thus, at the proper times in the operation of said machine, said awl is caused to enter the work and form an opening that will facilitate the entrance of the fastener sufficiently to be driven. While in the work said awl is caused to 80 move transversely to the left to feed the work into position with said opening directly beneath the driver, now in its elevated position. Thereafter said awl is elevated 85 free from the work and is returned again 85 transversely to the right into starting position, substantially simultaneously with which the nail carrier is advanced into position directly over the awl opening to present its nail to be driven by the driver as the latter 90 descends. The two pairs of cams for operating the two yokes 58 and 76, are in effect single cams only, since each pair operates but a single yoke, one being a leader and the other a follower so to speak.

95 While it is possible so to shape the cams for operating the awl as to give to the awl the required rapidity of movement necessary to cause it to clear itself of the descending driver, it is desirable to supplement such 100 cam action by means operated by the driver bar itself, in order that the movement may be accelerated while preserving an easy motion, and also to make certain that the said awl is always displaced in time and by the 105 device which it must clear. For this purpose the driver bar, (see Fig. 13) is provided near its lower end, with a vertical slot 81, offset near its lower end, and which receives a roller stud 82, projecting laterally. 110 from a horizontally arranged slide bar 83, mounted in the machine head. This slide bar at its outer end, at the right Fig. 13, is slotted to engage a crank pin 84, on a flange 85 of a hub 86, which is mounted in the machine head and within which is an eccentric bearing for the fulcrum shaft 72, of the awl moving lever. As the driver bar descends and before the driver has had time to overtake the awl, said cam slot 81 throws the 115 slide bar 83 to the left, and thereby turns the crank pin 84 and its hub to the left, throwing the eccentric bearing for the fulcrum shaft 72 to the right and imparting thereby, through the lever 71, a quick outward or clearing movement to the awl, in addition to the movement subsequently to be given it by the cams acting within the yoke 76. On the return or upward movement of the driver bar, the fulcrum shaft 72 is returned to its 120 125 130

innermost position thus, in a different direction, again supplementing the cam action of the yoke 76.

The machine described is particularly adapted to operate at high speed; all the cams are relatively small so that there is little inertia to overcome in starting and stopping them and the motions communicated from them to the various parts are all easy and capable of operating at high speed. The mechanisms themselves are simple and not easily thrown out of adjustment, so that the quality of work produced is of the best. All the motions are adjustable to the necessary extent to fit the machine for driving fasteners of varying shapes and sizes.

What I claim as new and desire to secure by Letters Patent of the United States is:—

1. A nailing machine comprising in combination nail driving means, a reciprocable awl bar, an awl transversely movable on said bar, means to positively move said awl transversely in both directions, including adjusting devices to vary the extent of the transverse movement, and means to reciprocate said bar.

2. A nailing machine comprising in combination nail driving means, an awl bar and its awl, a shaft and means to move the awl transversely from said shaft, and additional transverse awl moving means operated by the nail driving means.

3. A nailing machine comprising in combination nail driving means including a reciprocable driver bar, an awl bar, means to reciprocate it endwise, an awl transversely reciprocable on said bar, a shaft, means operated from said shaft to impart transverse reciprocation to said awl and means connecting said awl with said driver bar to additionally reciprocate said awl transversely therefrom.

4. A nailing machine comprising in combination a nail carrier, a shaft, a cam geared thereto to reciprocate said nail carrier, a

driver bar, a cam on said shaft to reciprocate it in both directions, an awl bar, an awl transversely movable thereon, means operated from said shaft to reciprocate said awl bar and also the awl thereon, relative to said bar, and means connecting the awl with said driver bar for moving the awl transversely from said bar during its approach stroke. 50

5. In a nailing machine, the combination with an awl and means to reciprocate said awl both vertically and transversely, of a slotted driver bar, means to reciprocate said bar, and a slide constructed and arranged to engage the transverse awl moving means and the slot, said slot being formed to impart transverse movement to said slide on reciprocation of the driver bar. 55

6. In a nailing machine, the combination with an awl and means to reciprocate said awl vertically, of prime means to reciprocate the awl transversely, comprising a pivotally mounted, oscillatory lever, a transversely movable awl-carrying slide connected to one end of said lever and actuating means connected to the other end of said lever, and secondary means to reciprocate the awl transversely, comprising an eccentric bearing for the fulcrum of said lever and means to rotate said eccentric bearing. 60 70

7. In a nailing machine, the combination with a vertically reciprocatory driver, a transversely movable awl and operating means for said awl, of a vertically movable cam, and connections between said cam and operating means to additionally move said awl, said cam being arranged to move in consonance with the driver. 75

In testimony whereof, I have signed my name to this specification in the presence of two subscribing witnesses.

MERTON D. PHELAN.
